TRACHEOTOMY KIT OR THE LIKE

Walter I. Bieger, Minneapolis, Minn., assignor to Arthur Salm Inc., Chicago, Ill., a corporation of Illinois

Filed Aug. 3, 1965, Ser. No. 86,419

Term of patent 14 years

(Cl. D83—12)

FIG. 1 is a top plan view of a tracheotomy kit incorporating the new design;

FIG. 2 is a side elevational view thereof;

FIG. 3 is a rear end view thereof;

FIG.

FIG. 5 is a reduced elevation partially broken away and shown in section with the knife and scissors disclosed in an extended position; and

FIG. 6 is a reduced side elevational view thereof with the surgeon's blade support in position and the surgeon's blade shown in broken lines in position for use.

The dominant features of my design reside in the portions shown in full lines.

I claim:

The ornamental design for a tracheotomy kit or the like, substantially as shown and described.
